(57) **CLAIM**

The ornamental design for a golf club sensor housing, as shown and described.

DESCRIPTION

FIG. 1 is a top perspective view of a first embodiment of a golf club sensor housing;

FIG. 2 is a bottom perspective view of the golf club sensor housing of FIG. 1;

FIG. 3 is a top view of the golf club sensor housing of FIG. 1;

FIG. 4 is a bottom view of the golf club sensor housing of FIG. 1;

FIG. 5 is a front view of the golf club sensor housing of FIG. 1;

FIG. 6 is a rear view of the golf club sensor housing of FIG. 1;

FIG. 7 is a left side view of the golf club sensor housing of FIG. 1;

FIG. 8 is a right side view of the golf club sensor housing of FIG. 1;

FIG. 9 is a top perspective view of a second embodiment of a golf club sensor housing;

FIG. 10 is a bottom perspective view of the golf club sensor housing of FIG. 9;

FIG. 11 is a top view of the golf club sensor housing of FIG. 9;

FIG. 12 is a bottom view of the golf club sensor housing of FIG. 9;

FIG. 13 is a front view of the golf club sensor housing of FIG. 9;

FIG. 14 is a rear view of the golf club sensor housing of FIG. 9;

FIG. 15 is a left side view of the golf club sensor housing of FIG. 9; and,

FIG. 16 is a right side view of the golf club sensor housing of FIG. 9.

The broken lines shown on the drawings form no part of the claimed design.

1 Claim, 8 Drawing Sheets
